UNITED STATES PATENT OFFICE.

THOMAS W. SIMMONS, OF GREENVILLE, SOUTH CAROLINA.

BUILDER MOTION.

Application filed February 28, 1924. Serial No. 695,779.

To all whom it may concern:

Be it known that I, THOMAS W. SIMMONS, a citizen of the United States, residing at Greenville, in the county of Greenville and State of South Carolina, have invented certain new and useful Improvements in Builder Motions, of which the following is a specification, reference being had to the accompanying drawings.

10 This invention relates to bunch building or forming devices for spinning machines, and particularly to certain improvements on the bunch building mechanism illustrated in my application for patent filed May 29, 1923, Serial #642,298. Inasmuch as the mechanism in detail is fully illustrated and described in this pending application, it is not necessary to go fully into the details of the mechanism in the present case and 20 only sufficient of the mechanism has been described and illustrated to render the present invention understandable.

The mechanism illustrated in my prior application was so designed as to provide a 25 bunch builder which included a rectilinearly movable supplemental cam having a sinuous cam track which acted to cause short reciprocations of the rocker arm and the ring rail or traverse connected thereto whereby to lay 30 the bunch upon the spindle, this cam being automatically put in operation when the ring rail was lifted after doffing and the cam acting to hold the main builder arm out of engagement with the main cam operating 35 this builder arm and to give short oscillations to the builder arm until the bunch is completely formed and then to automatically permit the usual building cam to operate upon the builder arm to cause the usual 40 traverse of the ring rail.

One of the objects of the present invention is to provide means whereby the bunch may be laid with a filling wind in place of a wind disposed entirely at the same point, or in 45 other words simply wound around one portion of the spindle instead of the wind being gradually raised.

A further object is to provide means whereby the amount of filling wind laid upon the spindle may be controlled, said means being adjustable so as to permit the cam which operates the bunch building mechanism to move through a more or less extent of its complete traverse.

55 A still further object in this connection is to provide a stop mechanism for the pur-

pose above described which includes a pin carried upon the supplemental or bunch building cam, this pin being adjustable into any one of a number of apertures in the bunch building cam, the pin engaging the stop when the bunch building cam has been shifted to its initial position ready for a new operation and controlling the initial position of this bunch building cam.

60 Other objects will appear in the course of the following description.

My invention is illustrated in the accompanying drawings, wherein:—

Figure 1 is a fragmentary front elevation 70 of a portion of a spinning frame of ordinary construction showing my invention applied thereto;

Figure 2 is a rear elevation of the builder motion with my improvements thereon;

Figure 3 is a section through the supplemental cam and an elevation of the associated mechanism;

Figure 4 is an elevation of the improved supplemental cam.

In the drawings, 10 is the end frame of a spinning frame, 11 and 12 the upper and lower rails of the ladder, and 13 an intermediate extension. The ladder carries the spindles 15 upon which operates the ring rail 14. The ring rail is caused to traverse vertically, as usual, by the vertical guide rods 16 connected to the ends of the bell crank levers 17, these levers having vertical arms 19 connected by suitable connecting rods 20. I have shown only one bell crank lever 17. This is mounted in a hanger 18.

Extending across the machine is the usual supporting rail 21, and carried on the extension 13 and the end frame 10 is the cam shaft 22 carrying a cam 23 shown as a tri-lobed filler cam. The builder arm 25 is pivoted to the hanger 24 and carries upon it the winding drum 26, over which the builder chain 27 is wound. This chain passes over a pulley 28 and from thence extends to the upper end of arm 19 and is connected thereto by a link 29. The drum 26 carries a worm gear engaged by a worm 31, the worm shaft carrying at the outer end of arm 25 the ratchet wheel 22 which is provided with the pawl 33 to secure a step by step motion of the ratchet wheel. The crank 34 is provided in order to operate the worm shaft by hand.

When the arm 25 rises under the action 110 of the cam 23 a dagger, as usual, strikes the pawl and releases it, permitting the release

of the ratchet wheel 32 one step and the consequent release of the drum a sufficient amount to permit a predetermined length of chain 27 to be slackened off. This can only occur when the builder arm has moved through its full stroke under the action of cam 23. So far, I have described the ordinary builder motion for a filler wind.

The attachment as covered in my prior

- 10 application covers a rectilinearly movable cam 35 having rack teeth 36 on its upper edge, while its lower edge has a sinuous cam track 37. The opposite faces of the cam have longitudinally extending recesses 38.
- 15 Hangers 39 depend from rail 21, which hangers support the longitudinally extending rails 43. The recesses 38 in the cam engage these rails 43 and thus the cam 35 can move longitudinally along the rails.
- 20 A spring 45 acts to draw the cam to the right in Figure 1 and resist movement to the left. The supplemental cam operates in front of the main cam 23 and when in operation prevents the engagement of the builder arm by the main cam, and it is to be noted at this point and it is one of my improvements over my mechanism shown in my prior application that the teeth 37 of the supplemental cam are disposed at an inclination to the horizontal, so that while all the teeth will give the same amount of traverse to the arm, the first tooth will cause the traverse of the arm 25 which will cause the thread to be laid at the base of the bobbin; the next tooth will give the same traverse but will cause the thread to be laid a little higher up, and so on until the final tooth is reached.

The rear end of the supplemental cam track 37 is carried upward and rearward, as at 48, to a point above the valleys of the cams 37 so that when the roller 47 moves onto this relatively long inclined base 48, the roller will travel up this base and permit the roller 47 to engage the main cam 43, which will then operate on the builder arm 25. The opposite end of the cam 37 is also formed with an inclined face 37a. To shift the cam member 35 a pinion 49 is mounted on shaft 22, which pinion engages the rack teeth 36. The pinion rotates with the shaft but is longitudinally shiftable upon the shaft, and to this end is provided with a spool 50 having the usual annular groove.

- 55 Mounted in a bracket 51 is a shifter rod 52 which engages the annular groove or spool 50 and slides through the bracket 51 and is urged in a direction to carry the pinion 49 into engagement with the teeth 36 of a spring 53. Mounted on arm 19 is a lug 54 which strikes against the end of rod 52 and shifts this rod to the left against the action of spring 53, thus shifting gear wheel 49 into mesh with rack 36. When arm 19 moves reversely, however, the spring 53 will

act to shift the rod 52 toward the right in Figure 1. As the arm 17 is connected to the traverse or ring rail 14, it follows that when the ring rail is depressed to doff the spindles, the lug 54 will be carried against rod 52 and force the rod laterally against the tension of the spring 53, thus shifting the pinion 49 toward the cam 23 and out of engagement with the rack 36. When arm 19 is returned to its initial position by reason of the lifting of the ring rail after doffing, spring 53 acts to return rod 52 and shift the pinion 49 into engagement with rack 36.

A pawl 55 pivoted on rail 21 prevents the return of cam member 35 after it has reached the end of its motion toward the right. Pawl 55 has a tail 56 connected by a normally slack cord 57 to the end of arm 17. Thus when this arm is fully depressed, the pawl 55 will be lifted from its engagement with the cam member 37.

So far, except for the fact previously stated that the teeth 37 of cam 36 are inclined to the horizontal, I have described mechanism which is fully illustrated and described in my prior application. The inclination given to the teeth 37 is one of the improvements over the construction previously described, and another improvement consists in providing on the cam member 35 a series of stop holes 58 within which a pin 59 is adapted to be disposed. I have shown six of these stop holes, numbered from 1 to 6, the first stop hole being that one nearest to the spring 45. Coacting with the stop pin 59 is a stop 60 which depends from one of the rails 43 and is disposed in the path of movement of the pin 59. The operation of these new parts will be described later.

The operation of the mechanism as a whole will be understood from what has gone before but, generally speaking, the operation is as follows: When the bobbins on the spindles are full, the tender depresses the ring rail fully downward to doff the spindles. The full depression of the ring rail shifts the lug 54 to the left as in Figure 1, thus shifting the pinion 49 out of engagement with the rack, which is at this time in a position slightly beyond that shown in Figure 1. The downward movement of the ring rail and the subsequent unwinding of the drum 32 will tighten the connection 57 and cause the pawl 55 to be lifted and the spring 45 will retract the supplemental cam to its initial position or to a position where the pin 59 is stopped by the stop 60.

When the winding machine is started up again, the rotation of shaft 22 causes the rotation of the pinion, shifting the supplemental cam toward the left in Figure 1, and the sinuous cam track gives oscillations of short amplitude to the builder arm, these

oscillations being progressively caused to move up the spindle by reason of the inclination given to the teeth 37. When the end of the cam has moved off the roller 47, the main cam will engage the roller and a full traverse will be given to the builder arm, and the drum 32 will be given a step by step motion to wind up the chain, thereby raising the ring rail toward the 10 upper portion of the spindle. Assuming that the stop pin 59 is inserted in #6 hole in the supplemental cam, then when the cam starts its travel there will be five traverses made by the ring rail forming the bunch and the maximum amount of yarn will be used in forming the bunch. Should it be desired to use a less amount of yarn in forming the bunch, the pin 59 is located in one of the succeeding holes 5, 4, 3, 2 or 1, as 15 the case may be, which will determine the number of traverses to be made by the arm 25. Thus the location of the stop pin 59 in any one of the holes 58 will determine the distance the cam 35 will be retracted by 20 the spring 45. It will be seen that the inclination of the teeth 37 will give a filling wind for the bunch which makes the bunch much more stable than it otherwise would be and the stop arrangement provides means 25 whereby the amount of yarn to be placed on the bunch may be regulated.

In forming the bunch with the mechanism of my prior application as modified by the present application, the bunch is begun at the lowest point of the traverse and as the cam 35 is driven by the pinion, each successive layer of yarn is placed a little higher up on the bobbin. This form of cam will allow putting on more yarn per bobbin and this method of winding the yarn will prevent any tendency of the bunch to slough off. It will be seen that by the use of this one reciprocating cam and the sliding gear wheel 49 that I accomplish, without any additional mechanism for operating the pick gear, the same result as is accomplished in other bunch laying motions and builder motions known to me where complicated systems of levers and springs are used.

50 I claim:

1. The combination with the builder motion of a spinning machine including an oscillating builder arm and a main cam, of a supplemental bunch building cam adapted to coat with the builder arm and when in operation holding the builder arm out of engagement with the main cam, means for shifting said supplemental cam a predetermined distance in one direction until a bunch is formed, the supplemental cam at this time moving out of engagement with the arm and permitting the builder arm to engage the main cam, means for holding said supplemental cam in the last named position, means for releasing said holding

means to permit the supplemental cam to return to its initial position when the ring rail of the spinning machine has been depressed, and means for adjustably limiting the return movement of the cam. 70

2. The combination with the builder motion of a spinning machine including an oscillating builder arm and a main cam, of a supplemental bunch building cam adapted to coat with the builder arm and when in operation holding the builder arm out of engagement with the main cam, means for shifting said supplemental cam a predetermined distance in one direction until a bunch is formed, the supplemental cam at this time moving out of engagement with the arm and permitting the builder arm to engage the main cam, means for holding said supplemental cam in the last named position, means for releasing said holding means to permit the supplemental cam to return to its initial position when the ring rail of the spinning machine has been depressed, and means for adjustably limiting the return movement of the cam comprising a fixed stop and a movable stop, one stop being rigidly supported in the path of movement of the other stop and the other stop being mounted upon the cam. 80 85 90

3. The combination with the builder motion of a spinning machine including an oscillating builder arm and a main cam, of a supplemental bunch building cam adapted to coat with the builder arm and when in operation holding the builder arm out of engagement with the main cam, means for shifting said supplemental cam a predetermined distance in one direction until a bunch is formed, the supplemental cam at this time moving out of engagement with the arm and permitting the builder arm to engage the main cam, means for holding said supplemental cam in the last named position, means for releasing said cam to permit the supplemental cam to return to its initial position when the ring rail of the spinning machine has been depressed, means for adjustably limiting the return movement of the cam comprising a pin mounted upon the cam, the cam having a series of perforations, in any one of which the pin is adapted to be disposed, and a stop fixedly mounted in the path of movement of said pin. 100 105 110 115

4. The combination with the builder motion of a spinning machine including an oscillating builder arm and a main cam, of a rectilinearly movable bunch building cam adapted to operatively engage the arm, means for putting said cam in operation after doffing, and means for automatically rendering the bunch building cam inoperative and the main cam operative when the bunch has been formed, said bunch building cam having its cam face disposed at an inclination to its path of travel to thereby 120 125 130

cause the progressive lifting of the traverse rail while the bunch is being formed.

5. The combination with the builder motion of a spinning machine including an oscillating builder arm, of a rectilinearly movable bunch building cam adapted to operatively engage the arm, means for putting said cam in operation after doffing, means for automatically rendering the bunch 10 building main cam operative and the main cam operative when the bunch has been

formed, said bunch building cam having a series of pin-receiving apertures in its length, a stop pin adapted to be disposed in any one of said apertures, and a stop fixed 15 in the path of movement of the pin and limiting the return movement of the bunch building cam to its initial position.

In testimony whereof I hereunto affix my signature.

THOMAS W. SIMMONS.
